(57) **CLAIM**

The ornamental design for a support block with long wings, as shown and described.

DESCRIPTION

FIG. 1 is a perspective view of my new design for a support block with long wings;

FIG. 2 is a first side view of the support block of FIG. 1; FIG. 3 is a second end view of the support block of FIG. 1; FIG. 4 is a top plan view of the support block of FIG. 1; FIG. 5 is a first end view of the support block of FIG. 1; FIG. 6 is a second side view of the support block of FIG. 1; and,

FIG. 7 is a bottom plan view of the support block of FIG. 1. The broken lines shown in FIGS. 1-7 are for illustrative purposes only and form no part of the claimed design. The unshaded areas of the interior of the support block likewise form no part of the claimed design.
